ATTACHING DEVICE FOR BAG FRAME
FASTENERSHoward J. Murphy, Greenwood, Mass., assignor
to United-Carr Fastener Corporation, Cam-
bridge, Mass., a corporation of Massachusetts

Application May 22, 1937, Serial No. 144,213

6 Claims. (Cl. 292—87)

My invention relates to bag frame structures in combination with an attaching member for the same and has for its main object to provide a preformed attaching member of simple construction adapted to be directly assembled with a bag frame member without the use of machinery.

In the drawings, which illustrate preferred embodiments of my invention:

Fig. 1 is a fragmentary plan view of a bag frame structure and one form of attaching member for the same, the ornament being omitted;

Fig. 2 is a section taken along the line 2—2 of Fig. 1, with an ornamental knob assembled with the attaching member;

Fig. 3 is a section taken along the line 3—3 of Fig. 1;

Fig. 4 is a side elevation of a portion of the installation shown in Fig. 1;

Fig. 5 is a section taken along the line 5—5 of Fig. 3 showing only the frame member with which the attaching member is assembled;

Fig. 6 is an end view of my attaching member per se;

Fig. 7 is a bottom plan view of the attaching member shown in Fig. 6;

Fig. 8 is a view similar to that of Fig. 7 but showing the manner in which one form of ornamental knob means is assembled with the attaching member;

Fig. 9 is a view similar to that of Fig. 7 showing the method by which another form of ornamental knob is assembled with the attaching member;

Fig. 10 is an end view of the knob and attaching member shown in Fig. 9;

Fig. 11 is an enlarged section taken along the line 11—11 of Fig. 9;

Fig. 12 is a fragmentary top view of a bag frame structure and a modified form of fastening member for the same;

Fig. 13 is a section taken along the line 13—13 of Fig. 12 with an ornamental knob means assembled with the fastening member;

Fig. 14 is a section taken along the line 14—14 of Fig. 12; and

Fig. 15 is a section taken along the line 15—15 of Fig. 12 showing only the frame member with which the attaching member is assembled.

Referring to the drawings, I have shown a fragmentary pair of frame members 1 and 2 interlocked in closed position by means of fastening or locking members, one of which I shall term my preferred form of attaching member. The frame members 1 and 2, with which my improved attaching members are preferably used, are of

the U-shaped cross-section type, as best illustrated in Figs. 2 and 13, having an outer wall 4, an inner wall 5 and a bottom wall 6 connecting the walls 4 and 5. The walls 4 and 5 are spaced apart to form an outwardly-opening channel, as most clearly illustrated in Figs. 2 and 13. The inner wall 5, in my preferred form, has a flange 7 integral therewith and extending in substantially right-angular relation to said inner wall in the direction of a continuation of the vertical plane of the outer wall 4. The flange 7 has a rectangular aperture 7a therein adapted to receive attaching portions of the attaching member for securing the attaching member to the frame, as will be described. It will be noticed that in the bag frame structure, with which I have chosen to illustrate my invention, the outer wall 4 is bent away from the inner wall 5 so that bag material (not shown) may be brought over the outer wall of each of the frame members and clenched in the channel between the inner and outer walls by a subsequent bending of the outer wall toward the inner wall.

The frame members 1 and 2 are held in locked position by a separable attaching member, as most clearly shown in Figs. 2 and 13, which, in both forms of my invention, comprises a main attaching member 8 secured to the frame member 1 and having means either integral with itself or provided as part of an ornamental knob, which may be assembled with the attaching member, which is adapted for interlocking engagement with cooperating interengaging means carried by the frame member 2, such as the projection 9 (Figs. 2 and 13), pressed from the material of the flange 7 of the last-mentioned frame member. Although I prefer to use my improved attaching members with frame members of the type described, it should be understood that my attaching members may be advantageously and quickly snapped into assembly with other forms of frame members in the manner hereinbelow set forth so as to provide an efficient means for separably securing the frame members together.

My preferred form of attaching member 8, as illustrated in Figs. 1 through 11, comprises a plate portion 10 having an ornament-supporting flange 11 at one end extending in substantially right-angular relation to the plate 10 and a base portion 12 (Fig. 3) at the other end. The base portion 12 has a foot portion 13 extending in an opposite direction relative to the plate 10 from that taken by the flange portion 11. The foot portion 13 is useful as an aid to maintaining the plate member in fixed position within the cross-

section of a frame member, but I do not wish to be limited to the same because satisfactory attachment of the attaching member to the frame member has been provided with this portion omitted. In order that my attaching member may be manually snapped into secure assembly with one of the frame members, I have provided, in my preferred form, attaching portions comprising a pair of legs 14, each of which extends upwardly from the base portion 12 on each side of the plate 10 (Fig. 3). The legs 14 are spaced from the plate 10 so as to permit a lateral yielding action relative to the same, and, in my preferred form, have their outer edges in diverging relation one to another in order that the legs may be cammed toward each other during insertion through the aperture 7^a. The legs 14 have their planes normally offset laterally relative to the plane of the plate 10, as most clearly shown in Figs. 2, 5 and 6, in order that the plate 10 may move toward and away from the legs 14 during opening and closing of the bag frame members, as will be hereinafter more fully described. At the outer ends of the legs 14 I have provided shoulders 15 adapted to engage material of the flange 7 adjacent the aperture 7^a when the attaching member is in final assembly with a frame member and relatively narrow projecting portions 16 formed as a continuation of the outermost ends of the legs 14 adapted to extend through the aperture 7^a and engage the material of the flange 7 adjacent one of the longitudinal sides of the aperture (Figs. 2 and 5).

A fastener socket means 17 (Figs. 2, 6 and 7) may be provided, in my preferred form, as an integral part of the flange 11 and adapted for cooperative fastening engagement with the projection 9 of the other frame member. The socket means 17 is preferably formed by bending a portion of the material of the flange 11 adjacent a side thereof downwardly to form a substantially hook-shaped portion, as most clearly shown in Figs. 2 and 6. However, I do not wish to be held by the specific fastener means 17 provided by the attaching members 8 for interlocking engagement with the cooperating portion 9 because it is apparent that modifications may be made in the form of the fastener means, or a satisfactory fastener means may be provided as part of an ornamental knob mounted upon the flange 11 without departing from the spirit of the invention.

In order to facilitate disengagement of the interlocking means of the frame member and to improve the appearance of the hand bag structure, I have preferably assembled an ornamental knob means 18 with the flange 11 of the attaching member.

The knob means may be of any suitable shape or material and assembled with the flange 11 in any satisfactory manner. In Figs. 2 and 8 I have shown an ornamental knob means having a substantially rectangular cross-section secured to the flange 11 through means of attaching members 19 (Fig. 8) extending through apertures 20 (Figs. 5 and 7) in the flange 11 into the body of the knob 18. In Figs. 9 through 11 I have shown another form of knob member which preferably comprises a substantially plate-like portion 21 having a groove 22 formed in its bottom face with converging side walls 23 extending the length of the knob 21 adjacent the groove 22 so as to provide a channel. Assembly of the knob 21 with the attaching member is effected by entering an end of the flange 11 into the channel and sliding the flange endwise of the channel until the flange

is properly positioned with its ends terminating short of the outer ends of the channel. Next, indentations are formed in the material of one of the side walls 23 adjacent the groove 22 between the outer ends of the flange 11 and the open ends of the channel providing projections 24 extending into the channel (Fig. 11) so as to limit lengthwise movement of the flange 11 relative to the channel in either direction. As a result of this construction, the knob means is securely affixed to the attaching member and is conveniently actuated for disengaging the interlocking means which hold the frame members in closed position.

Assembly of my first form of attaching member with the frame member 1 is a relatively simple matter and, in most cases, may be carried out by hand through moving the foot portion 13 into the aperture 7^a of the flange 7 and exerting force in a downward direction upon the flange 11 or an ornamental knob means mounted upon the same to move the foot portion 13 toward the bottom wall 6 of the frame member. As a result of the fact that the distance between the outermost edges of the legs 14 is greater than the lengthwise dimension of the aperture 7^a, the legs 14 are contracted toward each other until the diverging edges of the legs have passed through the aperture, at which time the legs expand so as to engage the shoulders 15 behind the material of the flange 7 adjacent the aperture 7^a, as most clearly shown in Fig. 3. When the attaching member is in final attached position with the frame member 1, a broad surface of the plate 10 preferably engages the longitudinal side of the flange 7 nearest the inner wall 5 and broad surfaces of the projections 16-16 engage material of the flange 7 adjacent the opposite side of the aperture 7^a, as most clearly shown in Figs. 2 and 5. As a result of the fact that the projections 16-16 engage material of the flange 7 adjacent the outer side of the aperture 7^a, the plate 10 is yieldable toward and away from the legs 14 when pressure is exerted upon the operating flange 11 or a knob means mounted on the same whereby the hook-shaped portion 17 may be engaged with 45 or disengaged from the cooperating fastener element 9 of the frame member 2. The foot portion 13 is positioned within the channel of the frame member 1 when the attaching member is in final position and may engage either the wall 4 or the wall 6 of the frame member to aid in maintaining the attaching member in fixed assembly within the channel of the frame member.

My modified form of attaching member shown in Figs. 12-15 is particularly adaptable for use with frame members which are identical in form to the frame members 1 and 2 illustrated in Figs. 1-5, but instead of providing a single rectangular aperture in the flange 7 of the frame member 1 for receiving the attaching portions of the attaching member, I have provided a pair of spaced rectangular-shaped apertures 25, each of which is adapted to receive one attaching portion of the attaching member, as will be described. My modified form of attaching member illustrated in Figs. 13-15 comprises a pair of spaced plate portions 26 connected at one of their ends by an ornament-supporting flange portion 27 extending in substantially rectangular relation to the normal plane of the plate portions 26. Each of the plate portions 26 has a base portion 28 (Fig. 14) at its lower end having a foot portion 29 extending away from the plate 26 in an opposite direction to that taken by the flange portion 27. An attaching portion in the form of a leg 30

extends upwardly from the base 28 on the inner side of each of the plate portions 26 and in spaced relation to its respective plate portion whereby the attaching portions may yield laterally relative to the same during movement through the apertures 25. The planes of the legs 30 are normally offset relative to the planes of the plate 26 to permit yielding of the plate portions back and forth relative to the legs for the purpose described in connection with my first form of attaching member. At the free ends of the legs 30 I have provided shoulders 31 adapted to engage material of the flange 7 adjacent the ends of apertures 25 in the manner of the shoulders 15 of my first form of attaching member, and projecting portions 32 adapted to engage material adjacent a side of the apertures 25 for performing the same function as that carried out by the projecting portions 16 of my preferred attaching member.

20 In assembling my modified form with the frame member 1, the foot portions 29 are moved into the apertures 25 and pressure is exerted upon the attaching member to force the foot portions downwardly into the channel of the frame member. During this action, the inner edges of the legs 30 engage material of the frame 7 adjacent the inner ends of the apertures 25, and as a result of the fact that the said inner edges diverge toward their ends connected with the foot portions 29, the legs yield laterally relative to the plate portions 26 until their inner edges have passed through the apertures 25, at which time they expand to engage the shoulders 31 behind the material of the flange 7 adjacent the apertures 25, as most clearly shown in Fig. 14. When my modified attaching member is in final assembly with the frame 1, broad surfaces of the plate portions 26 preferably engage one side of the apertures 25 and broad surfaces of the projecting portions 32 engage an opposite side (Fig. 15) permitting relative movement of the plate portions 26 relative to the legs 30 when pressure is exerted upon the operating flange 21 or a knob means 33 which may be mounted on the flange (Fig. 13) for engaging and disengaging cooperating interlocking means of the attaching member and the frame member 2 in the manner described in connection with my first form of invention.

50 As a result of my invention, I have provided attaching members which may be fixed in assembly with a bag frame member through simply snapping portions of the attaching member through an apertured portion of the frame member. Thus I am enabled by my invention to assemble a preformed attaching member directly with a frame member without the necessity of performing any further operations upon the parts such as the well-known difficult and slow assembly of a hinge pin and/or a torsion spring. Furthermore, my fastener members are of simple and inexpensive construction and in every way capable of efficiently cooperating to hold a pair of frame members in detachable locked position.

65 I am aware that changes and modifications could be made in the forms of the attaching members and frame members with which I have chosen to illustrate my invention without departing from the scope and spirit of my invention and so I do not wish to be limited by the preferred embodiments of my invention illustrated and described because the scope of my invention is best set forth in the following claims.

I claim:

75 1. In a fastener structure for bag frames and

the like having cooperating frame members one of which has an opening therethrough of predetermined dimensions, a fastener element carried by the apertured member for movable cooperative engagement with the other member, and snap fastener means associated with said element including a yieldable attaching portion adapted to be inserted through said opening and of a character normally larger than the opening whereby the attaching portion may be passed through the opening and will tend to restore itself to its original condition thereby engaging the material of the frame member to be retained therein, and providing for lateral yield to effect the aforesaid movable cooperative engagement.

2. In a fastener structure for bag frames and the like having cooperating frame members one of which has an opening therethrough of predetermined dimensions, a fastener element carried by the apertured member for movable cooperative engagement with the other member, and snap fastener means associated with said element including a fastener plate having yieldable anchor means connected thereto adapted to be inserted through said opening and of a character normally larger than said opening whereby the yieldable anchor means will contract during passage through the opening and thereafter expand into locking engagement with the material of the frame members adjacent said opening, and providing for lateral yield to effect the aforesaid movable cooperative engagement.

3. In a fastener structure for bag frames and the like having cooperating frame members one of which has an opening therethrough of predetermined dimensions, a fastener element carried by the apertured member for cooperative engagement with the other member, and snap fastener means associated with said element including a fastener plate having yieldable anchor means connected thereto adapted to be inserted through said opening and of a character normally larger than said opening whereby the yieldable anchor means will contract during passage through the opening and thereafter expand into locking engagement with the material of the frame members adjacent said opening, said yieldable anchor means lying in planes offset from and angularly related to the plane of the fastener carrying plate to yieldingly urge the fastener member toward engaging position with its cooperating other member.

4. In a fastener structure for a bag frame having cooperating frame members one of which has an opening therethrough of predetermined dimensions, a fastener element carried by the apertured member for movable cooperative engagement with the other member, and means for securing said fastener element to said apertured frame member comprising a plate-like portion adapted to be inserted through said opening and disposed in angular relation to said fastener element, and yieldable anchoring means extending from said plate-like portion and spaced from said fastener element and of a character normally larger than said opening whereby said plate-like portion and anchor means may be passed through said opening, and the anchor means will tend to be restored to its original condition engaging the material of the frame to be retained therein, and providing for lateral yield to effect the aforesaid movable cooperative engagement.

5. In a fastener structure for a bag frame

- having cooperating frame members one of which has an opening therethrough of predetermined dimensions, a fastener element carried by the apertured member for cooperative engagement 5 with the other member, and means for securing said fastener element to said apertured frame member comprising a plate-like portion adapted to be inserted through said opening and disposed in angular relation to said fastener element, and 10 10 yieldable anchoring means extending from the opposite end of the plate-like portion in divergent relation thereto and in a plane offset therefrom and of a character normally larger than said opening whereby said plate-like portion and 15 15 anchor means may be passed through said opening, and the anchor means will tend to be restored to its original condition engaging the material of the frame to be retained therein.
6. In a fastener structure for bag frames and 20 the like having cooperating channel-shaped

frame members at least one of which is formed with an aperture therein of predetermined dimensions, a fastener element carried by the apertured frame member for cooperative engagement with the other member, and means for securing 5 said fastener member to the apertured frame member comprising a plate-like portion disposed in angular relation thereto and adapted to be inserted through said opening, an angularly extending foot portion engaging the bottom of said 10 channeled frame member formed on said plate-like portion at the end opposite the fastener element, and yieldable leg means extending from the foot end of the plate-like portion in divergent relation thereto, and adapted to be snapped into 15 engagement with the material of the frame after passage through said aperture, said plate-like portion and associated fastener element being yieldable transversely relative to said leg means.

HOWARD J. MURPHY. 20
